(57) **CLAIM**

The ornamental design for a tube fixation device, as shown and described.

DESCRIPTION

FIG. 1 is a perspective view of a tube fixation device showing our new design;

FIG. 2 is a bottom perspective view of the tube fixation device shown in FIG. 1;

FIG. 3 is a rear view of the tube fixation device shown in FIG. 1;

FIG. 4 is a front view of the tube fixation device shown in FIG. 1;

FIG. 5 is a right-side view of the tube fixation device shown in FIG. 1;

FIG. 6 is a left-side view of the tube fixation device shown in FIG. 1;

FIG. 7 is a top view of the tube fixation device shown in FIG. 1;

FIG. 8 is a bottom view of the tube fixation device shown in FIG. 1; and,

FIG. 9 is a perspective view of two of the tube fixation devices shown in FIG. 1 positioned on a positioning strap fixated around the head of a patient such that each of the tube fixation devices is placed at the entry point of a respective nostril of the patient.

The broken line showing is included for the purpose of illustrating unclaimed subject matter and forms no part of the claimed design.
